G. Smith, H. Brown, & J. A. Read of Philadelphia, Pa.

assignors to

Geo. Haag & Co. of Philadelphia (aforesaid)
Letters Patent No. 830, Dated September 16th 1856.

The schedule referred to in these Letters Patent, and making part of the same.

To all whom it may concern:

Be it known that we, Ganiel Smith, Henry Brown, and Joseph A. Read, of the City, and County of Philadelphia, and State of Pennsylvania, have produced a new and original Stove design, designated as "The Gem." And we do hereby declare that the following is a full, clear and exact description of the same; reference being had to the annexed drawing forming part of this specification, in which

Similar letters of reference in the several figures, denote the same part of stove and design.

The front plate A, of the upper portion of the stove is ornamented in bas-relief with scrolls a, foliage b, and figures c. Upon it is the feed door B, embellished with foliage d, around the open portion, and with scrolls e, across the opening. On this plate are the inscriptions "patented 1856," and "The Gem," in raised capitals and numerals. The configuration and arrangement of the several ornaments of this plate are fully set forth in figure 1.

The side plates C, are ornamented in bas-relief with foliage h, and scrolls i, arranged and configured as shown in figure 2, together with figures j, and projections k, connected with the scrolls i, and foliage h, making up the design was set forth in figure 2.

The plates F, enclosing the fire chamber, are of open casting made up of entwined foliage and branches T, M, N, formed and arranged as set forth in the drawing.

The base plate F, has the form shown in fig. 4, and is ornamented in bas-relief, with scrolls v, and sweeping foliage p, arranged and having the configuration shown in the drawing. This plate bears the following inscription in raised capitals "Patented, Cox, Haag & Cox, Philadelphia".

The plates G, enclosing a side chamber, have the form shown in the drawing, and are each ornamented in bas-relief with foliage q, at each corner. The sides and back each bear an ornament composed of foliage r, bands s, and scrolls t, arranged and configured as shown in the drawing. The ash pit door is ornamented with a figure in bas-relief, made up of, foliage, scrolls and bands as shown in figure 3.

Plate H, between plates F and G, and overhanging the latter, bears on its edge combined scrolls u, and figures v, arranged and configured as shown in the drawing.

Plate I, above plates F, is ornamented with entwined scrolls as shown in the drawing.

Top plate J, is ornamented in bas-relief, with a band w, around the opening, bearing projections x, foliage y, in the corners, and an opening R, of combined foliage and scrolls; the design, configuration and arrangement being as shown in figure 5.

The foot K, is ornamented with scrolls a, and foliage b, as shown in the drawing.

A upon the water cup is a cover P, of open casting, configured as shown in the drawing.

We claim as our production, the design, configuration and arrangements of the ornaments in bas-relief on the several plates herein before set forth and shown in the drawing, constituting the design of stove, designated as "The Geni."
